UNITED STATES PATENT OFFICE

ALLEN BRADFORD, OF PORTLAND, OREGON

AIRSHIP

Application filed August 6, 1928. Serial No. 297,709.

My invention relates to my United States patents dated and numbered respectively April 6, 1926, and numbered 1,580,004 and dated January 10, 1928, and bearing Number 5 1,656,137.

My invention relates to air ships of the lighter than air type and has for its primary object an air ship the upper inner body portion of which has a metal lining disposed 10 on its inner surface, and the outer or skin portion of which is covered with fabric to prevent skin friction in flight.

A further object of my invention consists in having tubes running longitudinally of the 15 ship that are so connected with the outside of the body portion that the tubes may be insulated from temperature leakage and that may be filled with cold air at higher altitudes and be maintained therein for cooling and 20 refrigerating purposes, when the ship is returned to lower and warmer air levels.

Still further objects of my invention relates to methods of inflating the body portion and filling the same with relatively pure hydrogen gas and maintaining the same in a relatively pure condition free from air contamination.

A further object of my present improvements relates to a simplified construction 30 wherein no frame work is disposed within the gas holding compartment and a gas holding compartment that is relatively free from bulkheads, partitions and the like.

And still further objects of my invention 35 consist in having compressor and exhausting elements wherein the lighter than air elements may be taken from the body portion of the ship and stored within tank compartments disposed within the ship and stored therein 40 under pressure thereby lessening the lifting capacity of the ship when required and which may again be released and readmitted within the body portion for lift purposes. The tanks may be filled with compressed air 45 and/or compressed air when required to serve as ballast.

And still further objects of my invention relate to the means provided for attaching the metallic shell to the supporting elements and for connecting the metallic shell and the

fabric shell to the supporting elements with a minimum amount of fastenings and in a manner that will maintain the joints in a tight and satisfactory working condition.

And still further objects of my present invention reside in a frame construction adapted for supporting the ship in a suspended condition during the inflating and deflating operation that will insure safety to the hull during such operations. 55

Still further objects reside in closures disposed at the forward end of the ship with remote controls for manipulating the same that will permit air to enter the tubes when desired. 60

With these and incidental objects in view, the invention consists in certain novel features of construction and combination of parts, the essential elements of which are set forth in the appended claims, and a preferred 65 form of embodiment of which is hereinafter shown with reference to the drawings which accompany and form a part of this specification. 70

In the drawings: 75

Fig. 1 is a side view of the assembled ship with the skin portion partially broken away to illustrate the inner construction of the same.

Fig. 2 is a fragmentary, longitudinal, 80 cross section view of the lower portion of the ship. The same being taken on line 2—2 of Fig. 1, looking in the direction indicated.

Fig. 3 is a vertical, cross section view, taken on line 3—3 of Fig. 1, looking in the direction indicated. 85

Fig. 4 is a fragmentary, cross section view of the outer frame and lining construction of the midsection of the upper portion of the ship. The same being taken on line 4—4 of Fig. 3, looking in the direction indicated. 90

Fig. 5 is a vertical, sectional view of the center strakes of the outer frame structure. The same being taken at the horizontal line of the greatest diameter of the hull and running fore and aft therefrom at either side of the hull. 95

Fig. 6 is a fragmentary, cross section view of the frame structure, illustrating the filler and exhausting connection in side elevation. 100

that leads directly to the pressure and exhauster pumps.

Fig. 7 is a vertical, cross section view, taken on the center line of the ship, the same being taken when the contents of the hull has been completely exhausted and the lower fabric lining has been raised completely as a result of the exhausting operation. The exhausting of the contents of the holder insures the same being filled with a pure supply of the lighter than air gas when the same is to be admitted.

Fig. 8 is a vertical, section view of one of the tubes disposed within the body portion of the ship and running longitudinally thereof.

In the construction of my new and improved air ship, I use a minimum of frame elements and confine the same to the essential parts of the hull or frame. In some regards I utilize the principle in a modified form of the balloon. The upper half of the longitudinal body portion of the ship is made of a plurality of frame elements that run for substantially one-half circle and to the inner portion of and connecting the frames I place relatively thin and light metallic sheets. The edges of the sheets being secured to the frame elements. The outer portions of the frames are covered with a fabric covering to lessen the flying resistance of the ship and to render the outer covering relatively smooth and free from objectionable projections.

Like reference characters refer to like parts throughout the several views.

I form the upper portion of my frame primarily of circumferential ribs 1, that are in spaced relationship with each other and spaced apart by metallic plates 2. Grooves 3 are formed within the side walls 4, of the frames 1, into which flanges 5, disposed upon the edges of the plates 2 are made to engage. An off-set 6 being formed within the plate to form the engaging flange. Clamping bars 7 are disposed at either side of the rib 1 and are secured to each other and to the ribs by threaded fastenings 8 that extend through the ribs and through the fastening bars. The metallic sheet 2 being made of a relatively light and thin metal, as aluminum, duraluminum and any other metallic compound that is relatively light and strong. The inner wall of the plate being made to finish substantially flush with the inner surface of the rib 1. Longitudinal bars 9 are disposed into the outer surface of the ribs 1, and are in spaced relationship with each other. A fabric sheeting 10 is placed upon the outer surface of the frame, thus formed, to limit air friction caused by propelling the ship through the air at relatively high velocities. The purpose of making the inner surface of the frame thus formed in a relatively smooth condition is to prevent the chafing of the inner lower lining of the ship during the inflating and de-

flating of the same occasioned by the filling of the ship body with the lighter than air elements used for affording buoyancy to the completed ship. Supporting rings 11 upwardly extend from each of the central ribs to which supporting elements are made to engage for supporting the ship during the conditioning of the same and the filling of the same for flight.

Depending from the upper circumferential ribs are a plurality of structural metallic transverse frames 12 composed of outer metallic elements 13 and inner metallic elements 14 with lacing bars 15 secured thereto, by any suitable fastening means. I preferably chamfer the lower end 16 of the rib 1 to form a feather edge 17 on its lower end and I chamfer the upper end 18 of the frames 12 to form a feather edge 19 on its upper edge and secure their respective engaging ends together by any suitable fastening means. The lower ends 20 of the frames 12 are secured together in spaced relationship through the medium of a latticed girder 21. The lower edge of the metallic plates 2 has a flange 22 disposed from its lower edge caused by an off-set 23 formed within the plate and the central stake 24 has a groove 25 disposed within its upper surface into which the flange 22 of the plate is made to engage. A fastening bar 26 is made to engage the upper surface of the off-set 23 of the plate and the plate is secured in position upon the horizontal stake 24 by any suitable fastening means, as by holding down bolts 100 27. The horizontal stake 24 is disposed at substantially the horizontal central line of the ship and runs substantially the full length of the same and is secured to the frame members 1, thus forming the inner upper body portion of the frame of a metallic crown. The bottom half of the inner portion of the ship is composed of fabric 28 which is secured to the inner side of the stake 24, by any suitable fastening means, as by a clamping bar 29. The clamping bar 29 being spaced apart from the inner surface of the stake 24 and the fabric lining 28 is placed therebetween, as illustrated in detail in Fig. 5. The fabric lining may be securely clamped by any suitable fastening means, as by fastening bolts 30. A promenade deck runs longitudinally of the ship structure and is supported upon latticed girders 31, the outer ends of which are supported upon the structural depending metallic frames 12. A promenade deck may be placed upon the latticed girders 31. Running longitudinally of the ship and disposed between the latticed girders 20 and 31 are a plurality of fluid holding tanks 32, here shown as two in number, but I do not wish to be limited to any specific number. An intercommunicating pipe system 33 connects the tanks 32 with suitable compressors 34 130

and pumping units 35 and the connection 36 leads into the interior of the body portion of the ship from the pipe systems; the purpose and object of which is to pump fluids into and out of the gas chamber 37 of the ship. One or more passageways 38 are disposed at the upper surface of the ship and communicate with the gas holding chamber 37 to which suitable exhausters may be attached.

When it is desired to fill the chamber 37 with the lighter than air gas, as hydrogen, it is highly desirable for safety reasons and other reasons that the hydrogen remain in a substantially pure state and by the exhausting of the chamber 37 through the connecting passageways 38, the inner fabric lining 28 of the ship will be drawn upward and into the dome like space disposed within the ribs 20 until the same may be substantially and completely exhausted of air, after which the hydrogen gas in a substantially pure state will be admitted into and between the lining of the ship and the gas bag disposed therein 25 be reinflated with substantially a pure supply of lifting gas, as hydrogen.

The control bridge of the ship is shown at 39 in Fig. 1, into which the motor controls and other manipulative elements are assembled. The quarters for passengers and crew are disposed at the bottom of the body member of the ship and are depending from the structural frames 12 and the latticed girder 21. The same being supported by any suitable structural side wall members 40 and 41. Openings 42 are disposed at either side for observation and ventilating purposes. I have here shown the ship as having four prime movers, one each being mounted at the stern of the ship, and one each being mounted on the forward end of the ship, with one pair on each side. Cross supporting girders 43 extend outwardly from the side walls 40 and 41 and supporting trusses 44 and 45 support the girders 43 upon the structural metallic transverse frames 12. A prime mover is mounted at the outer end of each of the supporting girders 43, as illustrated at 46 and 47 in Fig. 3. Suitable starting and lifting rudders are disposed at desirable locations upon the ship. In order that the tanks into which the lighter than air gas may be stored and/or air to be taken from the colder strata for refrigerating purposes, I build an insulated box like closure having back and end walls of insulated material, as shown at 48 and 49 into which the tanks are disposed. Hinged closures 50 and 51 are disposed at the forward end of the ship, the same being hingedly supported at their forward ends, as shown at 52 and 53 and each of which is manipulated by a positioning cam 54 with suitable control means being attached thereto and leading to the bridge deck, no particular claim being made for any specific manipulative elements.

The openings created by the movement of the wings 50 and 51 permit of the passage of the air through the tunnel 55 and through opening 56 directly into the insulated chamber 57 in which the storage tanks 32 are located. The purpose of placing the tanks 32 in the insulated chamber 57 is to aid in the refrigeration of the air and to aid in keeping the air in a refrigerated condition within the tanks. The storage tanks have an upper metallic wall 58, as illustrated in detail in Fig. 8, and have the lower half of fabric material so that as the contents of the tanks are exhausted through the outlet opening 60 the lower fabric portion will be drawn upward until it assumes the position, as shown in dotted line. The readmittance of the buoyant fluid, or the admittance of air thereinto will entirely fill the tank and the fabric lining 59 would be restored to normal position. Suitable connections are made at the meeting edges of the lining 58 and of the fabric 59, as shown at 61 and 62 the same may be made substantially as described for the meeting edges of the fabric 28 with that of the central horizontal strake 24.

While the form of mechanism herein shown and described, is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, the combination of ribs in spaced relation downwardly extending from the top of the ship to substantially the horizontal medial line of the ship body, aluminum alloy plates disposed between the ribs and secured to the side walls thereof to form a metal lined dome within the upper half portion of the inner body member, structural metallic transverse frames downwardly extending from the ribs and secured thereto, a central strake running longitudinally of the ship and secured to the ribs thereof, the lower edge of the metallic inner lining terminating at the central strake and secured thereto, and a fabric inner lining for the lower portion of the hull and secured to the central strake to form a gas holding bag for the lower portion of the hull.

2. In a device of the class described, the combination of an air ship frame of the lighter than air type, consisting of upper ribs maintained in spaced relation through metal plates disposed therebetween and secured to the walls of the ribs, structural metallic transverse frames depending from the ribs and secured thereto, latticed girders forming the floor supports running transversely of the ship and secured to the trans-

- verses frames, and a central longitudinal strake running entirely around the ship body and secured to the ribs and a fabric gas holding bag secured to the central strake and forming a lining for the lower portion of the ship body.
- 3: In a device of the class described, the combination in the frame of a lighter than air type, of spaced ribs forming the upper half of the frame structure, aluminum alloy plates disposed between the ribs on their inner side walls and secured thereto forming lining for the upper half of the inner walls of the hull, substantially horizontal longitudinal bars disposed the outer surface of the ribs, structural metallic transverse frames depending from the ribs, cross latticed braces connecting the lower ends of the transverse frame members and a gas holding fabric lining for the lower half of the inner frame and secured to the frame elements at substantially a longitudinal medial line and an outer fabric covering for the frame elements.
- 10 4: In a device of the class described, the combination of a frame formed of ribs spaced apart, transverse frames depending from the ribs and cross latticed braces secured to the lower ends of the transverse frame members, aluminum alloy plates connecting the ribs to their inner walls and longitudinal bars disposed in spaced relation upon the ribs and forming the outer skin support of the hull.
- 15 5: In a device of the class described, the combination of a frame comprising ribs spaced apart by metallic sheets forming the inner lining of the upper half of the hull, substantially horizontal bars disposed in spaced relation and running longitudinally of the ship to form an outer skin support, metallic structural transverse frames depending from the ribs and secured thereto, a gas holding bag of fabric forming the lower half lining of the hull and secured at its upper edge to a central strake running entirely around the ship and secured to the frame thereof.
- 20 6: In a device of the class described, the combination of a structural frame comprising ribs, transverse frames depending from the ribs and secured thereto and cross latticed braces formed in pairs and spaced apart, metallic sheets secured to the inner upper half of the frame to form a gas holding compartment and to give strength and rigidity to the frame, horizontal bars spaced apart and secured to the outer surface of the frame elements, a fabric gas holding bag disposed on the inner lower half of the frame and secured thereto and to the metallic plates to form a gas holding compartment of metal its upper half and of fabric its lower half and a fabric covered outer skin.
- 25 7: In a device of the class described, a fabricated frame composed of circumferential rib elements, said frame elements being metallic lined on its inner upper half and being fabric lined on its inner lower half, said fabric lining being secured to the frame on its upper edges at a point substantially on the longitudinal medial line of the frame and a fabric outer covering for the frame elements.
- 30 8: In a device of the class described, the combination of a framed structure composed of a ribbed frame, fastening elements maintaining the ribs in spaced relation, an inner upper lining of metal and an inner lower lining of fabric encompassing the inner frame to form a gas holding compartment, a fabric covering encompassing the outer frame and an insulated compartment running longitudinally of the frame and along the lower side of the frame.
- 35 9: In a device of the class described, the combination in a lighter than air ship frame composed of fabricated ribs downwardly extending to substantially the longitudinal central line of the ship frame, grooves disposed within the side walls of the frame elements, inner metallic lining elements having flanges terminating at the vertical edges of the sheets, said flanges adapted for engagement within the grooves of the frame elements, clamping bars adapted for engagement with off-sets disposed adjacent the flanges of the metallic linings, and common fastenings for the clamping bars, the metallic sheets and the frames.
- 40 10: In a device of the class described, the combination in a lighter than air ship frame; comprising ribs, grooves disposed within the side walls of the ribs, aluminum alloy sheets with flanges for engagement within the grooves of the rib elements, clamping bars for said sheets relative to the ribs, fastening elements for said clamping bars, and a horizontal central strake disposed on the lower end of the rib elements and means for locking the sheets relative to the central strake.
- 45 11: In a device of the class described, the combination in a lighter than air airship frame, of substantially vertical ribs spaced apart on their inner surface by thin and relatively light metallic sheets, and held together by common fastenings relative to the sheets and the ribs, and substantially horizontal longitudinal bars in spaced relation disposed upon the outer surface of the rib elements and supporting elements upwardly extending from each of the ribs.
- 50 12: In a device of the class described, the combination of a lighter than air airship, an insulated compartment running longitudinally of the ship, storage tanks disposed within the insulated compartments and means for admitting air into the insulated compartment while the ship is in flight.
- 55 13: In a device of the class described, the combination in a lighter than air airship having an insulated compartment running longitudinally of the ship, communicating with the

ments for admitting air into the compartment while in flight, storage tanks disposed within the compartment and means for pumping lifting gas from the gas holder of the ship into the tanks and for pumping lifting gas from the tanks into the gas holder.
